United States Patent Office

Des. 206,843
Patented Jan. 31, 1967

206,843

PORTABLE SPACE HEATER

John S. Taylor, Jacksonville, Fla., assignor to Tifcon Company, Jacksonville, Fla., a corporation of Florida

Filed Mar. 11, 1966 Ser. No. 1,415

Term of patent 14 years

(Cl. D81—19)

Fig. 1.

Fig. 2.

FIGURE 1 is a perspective view of a portable space heater embodying my new design; and

FIGURE 2 is a perspective view taken from the opposite side thereof.

The dominant features of my design reside in those portions thereof shown in solid lines.

I claim:

The ornamental design for a portable space heater, as shown and described.
